UNITED STATES PATENT OFFICE.

CLARENCE ADELBERT LEMEN, OF DETROIT, MICHIGAN.

LOW-WATER ALARM.

No.853,309.

Specification of Letters Patent.

Patented May 14, 1907.

Application filed July 22, 1905. Serial No. 270,805.

To all whom it may concern:

Be it known that I, CLARENCE ADELBERT LEMEN, a citizen of the United States of America, residing at the city of Detroit, in the county of Wayne, in the State of Michigan, have invented certain new and useful Improvements in Low-Water Alarms, of which the following is a specification described in such a manner that a person skilled in the art could manufacture the same.

This invention has reference to low water alarms and has for its object an alarm that shall be simple, useful and economical in construction and certain in its operation at different pressures of steam and consists in the combination and arrangement of devices described and specified herein, the description showing only one form in which the device may be operated.

20 In the drawings, Figure 1. is a perspective view with a portion of the water jacket tank broken away to show the interior and a cover of the same open. Fig. 2. is a vertical section explaining the interior arrangements.

25 B is a steam pipe: B' is the means for connecting same to the boiler.

A is a tank or water jacket surrounding the steam pipe B.

30 A' is a cover preventing evaporation of the water contained in the water jacket.

C is a casting supporting the thermometer bulb.

C' is an insulating material facing the casting C.

35 D is the glass of the usual mercurial thermometer consisting of a capillary tube having its exhaustion of air approaching a vacuum.

D' is the mercury contained within the 40 capillary tube.

E is the metal casing forming the prolongation of the casting C and containing the bulb of the thermometer and the packing surrounding.

45 g' is the bulb of the thermometer where the capillary tube is enlarged to contain a reservoir of mercury.

G is an insulated binding post connected to an electrical circuit. G' is the other binding post connected with the electrical circuit, each binding post is connected with a wire, the end of which is blown in the glass entering the capillary tube and these wires enter the tube at such a height that expansion of the mercury to a certain point causes a closing of the circuit.

H is a valve connected to the steam pipe B for the purpose of drawing off its contents.

E² and E' are the several parts of the stuffing box for the purpose of retaining the bulb 60 of the thermometer within the steam pipe B.

f is a seal for sealing the packing F within the casing E and surrounding the thermometer bulb g'.

g shows one of the wires connected with 65 the binding post G at a point where it is blown in the glass of the thermometer.

In operation the thermometer is set for the pressure of steam under which it is intended to operate and at such a point on the boiler 70 that the lowering of the water below the steam pipe B allows an inrush of vapor which causes expansion of the mercury and the mercury thereby rising in the tube makes connection of the electrical circuit through 75 the upper wire blown in the glass and the binding post. This closing of the circuit operates the signal device. The water jacket used with the setting of the thermometer allows the operation under different pressures 80 of steam from the lowest pressure used up to the highest in practical use. The mercury of the thermometer should be contained in a tube having an exhaustion of air as near a vacuum as possible.

Having described my invention, what I claim is:

1. In an electric low water alarm, the combination with a steam pipe, of a support for a mercurial thermometer forming a casing for 90 the bulb of same, wires blown in the glass of the thermometer connected with an electrical circuit so that the expansion of the mercury closes the circuit, a signal device in said circuit operated thereby, and a water 95 jacket surrounding said steam pipe.

2. In an electric low water alarm, the combination with a steam pipe surrounded by a water jacket, of a support for a mercurial thermometer forming a casing for the bulb of same capable of being inserted into the said steam pipe, wires blown in the glass of the said thermometer connected with an electrical circuit, a signal device in said circuit 100 said circuit being closed, and a signal device 105 operated by means of the expansion of the mercury contained in said bulb.

3. In an electric low water alarm, the combination with a steam pipe adapted to be connected to a boiler, of a contact device for closing the said circuit by expansion of the metal connected to the said steam pipe, a

water jacket surrounding the said steam pipe, and a signal device contained in the said circuit and operated thereby.

4. In an electric low water alarm, the combination with a steam pipe adapted to be connected to the boiler, of a device for operating a signal device by expansion of the metal consisting of or connected to the said steam pipe, a water jacket surrounding the said steam pipe, and a valve or means of drawing off the contents of the said steam pipe.

5. In an electric low water alarm the combination with a water jacketed steam pipe, of a bulb of a mercurial thermometer contained therein, wires blown in the glass of the thermometer connected with the electric circuit so that the expansion of the mercury closes the circuit and operates a signal device thereby, and compressible material contained in the casing fitting into the said steam pipe and surrounding the bulb of the said thermometer.

6. In an electric low water alarm the combination with a heater adapted to contain steam, of a steam pipe extending from the interior of the heater to the exterior, a water jacket surrounding the said steam pipe exterior to the said heater, a bulb of a mercurial thermometer contained in the steam pipe, wires blown in the glass of the thermometer connected with the electric circuit so that the expansion of the mercury closes the circuit and operates a signal device thereby and a casing surrounding the bulb of the said thermometer adapted to enter the steam pipe sufficiently to allow of surrounding of the said casing by steam from the boiler as and for the purposes specified.

In witness whereof I have hereunto set my hand in presence of two witnesses.

CLARENCE ADELBERT LEMEN.
